UNITED STATES PATENT OFFICE.

JOHN H. ALLEN AND FRANKLIN M. PATTERSON, OF PHILADELPHIA, PENNSYLVANIA.

PIPE-FLANGING MACHINE.

No. 867,383.

Specification of Letters Patent.

Patented Oct. 1, 1907.

Application filed March 25, 1907. Serial No. 364,254.

To all whom it may concern:

Be it known that JOHN H. ALLEN and FRANKLIN M. PATTERSON, of the city and county of Philadelphia and State of Pennsylvania, have invented an Improvement 5 in Pipe-Flanging Machines, of which the following is a specification.

Our invention has reference to pipe flanging machines and consists of certain improvements which are fully set forth in the following specification and shown 10 in the accompanying drawings which form a part thereof.

The object of our invention is to provide mechanical appliances which will be easily and speedily controlled and which, during their manipulation, will produce 15 the expansion of the end of the pipe in the flange or ring to which it is to be secured, the said operation being accomplished in an inexpensive manner and with the most satisfactory results as to strength, tightness of joint; and durability.

20 Our invention consists essentially in the employment of a sectional expanding die of special construction, combined with a reciprocating arbor and a suitable support for holding the expanding die sections in proper relation during the expanding operation.

25 More broadly, our invention comprehends the expanding die when formed with projections or ribs, integral or otherwise, upon the outer surfaces of the sections and which, when in alinement, form annular projections which exert direct outward pressure upon the 30 internal portion of the pipe for expanding the parts thereof which are in contact with the expanding die more or less into the annular recesses or grooves on the internal face of the flange to which the pipe is to be united, the contact being especially tight at the corner 35 edges of the said grooves.

Our invention further consists in providing a suitable frame work having means for supporting the sectional expanding die, and combined therewith a power cylinder and a reciprocating piston or plunger therefor, and 40 an arbor moved by the piston or plunger longitudinally through the sectional expanding die.

Our invention also comprehends details of construction which, together with the features above specified, will be better understood by reference to the drawings, 45 in which:

Figure 1 is a longitudinal sectional elevation of a pipe flanging machine embodying our invention; Fig. 2 is an end elevation of same; Fig. 3 is an elevation of our improved expanding die with a portion removed; Fig. 50 4 is an end elevation of same; Fig. 5 is an elevation of a modified form of our improved expanding die with a portion removed; Figs. 6 and 7 illustrate other modifications in the cross section of segments of the expanding die; Fig. 8 is an elevation of a pipe and flange with part 55 in section united by the employment of the dies shown in Figs. 1 and 3; Fig. 9 is an enlarged view of a portion

of the joint thereof; Fig. 10 is an elevation of the pipe and flange when formed by the employment of the dies shown in Fig. 6; Fig. 11 is an enlarged view of the joint in same; and Fig. 12 is an elevation of a pipe and flange 60 with part in section when united by the form of dies shown in Fig. 7.

A is the base or bed of the machine and may be of any construction.

B is a cast steel housing and is bolted to the bed. 65 Sleeved in this housing B is a hydraulic cylinder C, the same being clamped in position by means of a large screw collar D. The rear end of the hydraulic cylinder is closed by a head C' and the rear extension of the body of the cylinder is sustained by a divided support B' 70 clamping the cylinder and bolted to the bed.

E is a piston working in the cylinder and is secured to the piston rod or plunger E', which, for accuracy in alinement, is not only extended through the forward head of the cylinder but also through the rear head. 75 It is evident, however, that various forms of hydraulic cylinders and plungers may be employed for the purposes of our invention, but we have shown herewith that form which we have found excellently adapted to the purposes of our tool. Water or other power is 80 applied to this cylinder at either end as desired for reciprocating the piston and plunger. The end of the plunger is provided with a socket G in which the arbor H is secured in a detachable manner so that various sized arbors may be employed with the same machine. 85

F is a cast steel housing having a large circular aperture preferably formed with steps, as at i. This housing is bolted to the bed frame and is in alinement with the housing B and connected to it by strong bolts f whereby it is accurately and rigidly held in position 90 with relation to the hydraulic cylinder. The axis of the plunger and arbor is preferably central with the aperture in the housing F. Fitted to the aperture of the housing is a removable abutment ring I which is also stepped on its periphery to coöperate with the 95 steps on the housing F as indicated in Fig. 1. This abutment ring I is annular in form, having a central opening through which the smaller part of the expanding die J and arbor extend.

The expanding die J consists essentially of a series of 100 tapering segments arranged in a circle so as to form an annular die of special construction. The various segments making up the expanding die are held together by suitable springs L which are circular in form and are adapted to seats or apertures l in the segments. 105 The spring rings are preferably of solid steel wire split at one place in their circumference as indicated in dotted lines in Fig. 4. The cross section of the segments is clearly shown in the drawings and comprises a construction in which there is a radial flange K' 110 upon each of the segments K, and which flanges rest against the abutment ring I as shown in Fig. 1, said

abutment ring preventing the die from being thrust toward the pipe and away from the cylinder. The segments are further provided with transverse ribs k with or without ribs k' and these are formed upon the extension of the segment which constitutes the smallest outside diameter of the expanding die, either integrally or otherwise. The inner surface of the segment is made tapering as at K^2 in a longitudinal direction to correspond to the tapering of the arbor H . Furthermore, the segments are transversely curved on their inner and outer surfaces so that, when the several segments K making up the die are arranged side by side in a circle, the ultimate or complete die is substantially conical, that is to say it has a conical central aperture and its outer diameter is larger at one end than the other although the particular operating part of the die adjacent to the ribs k is preferably made cylindrical except for the extension of the said ribs, so as to be in practical alinement with the interior surface of the pipe when the expanding operation is completed.

The pipe is shown at P and the pipe flange is indicated at T , in Fig. 1. Referring to Fig. 8, it will be seen that the union of the pipe and the pipe flange consists in having the interior of the pipe expanded into one or more annular grooves at p and thereby forcing those portions of the pipe outwardly into the grooves t of the pipe flange.

By referring to Fig. 9, it will be seen that the actual joint, both for strength and tightness, is produced by the sharp corner edges of the grooves t of the pipe flange being embedded in the metal of the expanded portion of the pipe. It will, moreover, be seen that the pipe itself is not expanded tightly into the cylindrical portion of the pipe flange nor into the bottom of the annular groove t thereof. Such expansion is not at all necessary as we have found by careful experiment; and moreover, by avoiding this, there is less power necessary in producing the joint, and consequently, a very much smaller machine is required. Furthermore, it is evident that as there is more or less elasticity to metal, the metal of the pipe will have no reflex action where the expansion does not attempt to force it up to a continuous contact with the pipe flange, and consequently, the actual joints at the points S (Fig. 9) are more secure and tight than would be the case if an attempt were made to force the metal to the bottom of the grooves and against the inner surface of the flange throughout its length. Such construction is however somewhat modified when the pipe is of very ductile metal, such as copper, which has a tendency to retain its set position after being subjected to considerable pressure; but for wrought iron or steel pipes, we have found it more desirable that contact with the bottom of the grooves and the inner surface of the flange throughout their length shall not be employed.

When employing our improved machine for expanding pipe in its flange, the arbor H together with its operating mechanism is withdrawn from the die J . The pipe with the flange in place is then brought to the position shown in Fig. 1 and may be held by hand or any suitable convenient device. The expanding die J is then placed into the end of the pipe and with the flanges K' resting against the annular abutment ring I , and the arbor is then driven forward through the flange die to expand its sections and the annular ribs k

thereof are forced outward against the internal surface of the pipe, producing specific expansion thereof at localized places as indicated in Figs. 8 and 9. When the arbor is withdrawn, the die is retained by the pipe sufficiently long to release the die from binding upon the arbor, and after the withdrawal of the arbor, the die may be withdrawn from the pipe and the operation repeated.

It is evident that while we have shown two of these annular ribs k on the die, one or more may be employed as desired. Two are preferable, but in some cases one would be sufficient. For finish and further strengthening of the joint, we may provide two additional annular ribs upon the die sections, as indicated at k' , and this will produce the expanded portions at m, m' shown in Fig. 10 adjacent to the front and rear edges of the pipe flange, so that they will make the pipe fit tightly at these points as well as in the actual grooves in the pipe flange. It is, of course, evident that either one or both of said flanges k' may be employed as desired.

In some cases, the joint may be made as shown in Fig. 12. In this case, there is only one annular groove in the pipe flange. The face side, however, of the pipe flange is recessed adjacent to its inner edge as n . The preferred form of expanding die for this character of joint is shown in Fig. 7, in which the annular ribs k produce the expansion of the pipe to force it into the annular groove of the flange and in which the larger of the ribs k' produces the expansion of the pipe adjacent to the grooved edge of the pipe flange at n , and the smaller annular rib k' produces a slight expansion of the pipe at n' adjacent to the opposite end of the pipe flange. This illustration also indicates the use of a copper pipe and in which it is expanded tightly to the interior of the flange.

In the operation of flanging pipe by our improved machine, it is evident that the expansion of the die J will produce some separation between the several segments, and consequently these points of separation will not permit the die to act upon the pipe with the same effect as if there were no such gaps. To overcome this possible result, the expansion is preferably accomplished by two operations, that is to say, first expanding the die within the pipe to produce approximately the proper expansion, then collapsing the die somewhat, turning it slightly and once more expanding it to complete the operation before withdrawing the tool. In the use of the machine, it is preferable that it shall be operated in the customary manner wherein there are two accumulators, one to produce the rapid movements of the plunger wherein great power is not required, and the other to apply the final power as when producing the final results desired.

In Fig. 6, we have shown the spring L at one end of the die segments as placed over hooked portions constituting seats l in place of being put through the body of the die as shown in the other end and also in Figs. 3 and 6.

In Fig. 5, we show the ribs of the die formed of separate parts L' which also constitute the springs or at least a part of them for holding the die segments together. In this manner also there will be less breaking of joints in the alinement of the ribs. These

parts L' correspond to the ribs k and are included under the term "rib" employed in the claims.

By carefully examining Figs. 10 and 11, it will be seen that the actual grooves t in the pipe flange are not rectangular as in Fig. 8, but that the shoulders or corners of these grooves are turned with rectangular lateral grooves t' which form abrupt shoulders for the lodgment of the metal. It will be seen from Fig. 11 that in this case, not only do we have the annular 10 corners of the pipe flange entering the metal of the pipe, but we also have oppositely directed portions of the material entering the grooves in the pipe flange, thereby forming a double joint between the pipe and the flange and still without the main body of the 15 pipe flange and the bottom of its groove being reached by the metal of the pipe. This joint is perhaps better than the joint shown in Fig. 8 and is not materially more expensive. The principle of construction and mode of forming is, however, substantially the same.

20 We have described several joints between the pipe and flange which are produced by the employment of our improved dies and machine, and while we make no claim to said joints in this application, said joints will form subject matter of separate applications.

25 While our invention is designed for large work, in which a motive power, such as a hydraulic machine, is employed for operating the dies, it is evident that the machine may be made in suitable portable form in which the arbor might be driven in by hand power, 30 and therefore we do not confine ourselves to that form of our machine in which the die and arbor are combined other than by their direct connection in the act of expanding.

While we prefer the construction shown as being 35 most excellently adapted for the purposes of our invention, it is evident that the details may be modified without departing from the spirit of the invention.

Having now described our invention, what we claim as new and desire to secure by Letters Patent, is:

40 1. A pipe flanging device consisting of an annular die divided into sections and having its sections provided with circumferential ribs for acting on the interior surface of the tube to be expanded, combined with means for expanding the annular die, and means independent of the 45 annular die fixedly supported independent of the work acted upon for sustaining the die against longitudinal movement toward the pipe or the flange in which it is to be expanded and as a guide for the pipe for insuring its proper adjustment longitudinally with relation to the die.

50 2. A pipe flanging device consisting of an expanding annular die divided into sections and having the outer surfaces of its sections provided with circumferential retaining flanges and rib structure for acting on the interior surface of the tube to be expanded and their inner surfaces tapered to form a tapered aperture through the die, combined with tapered arbor to expand the die, an annular frame fixedly supported independent of the work and die and having a flat annular surface against which the flanges of the die rest to hold the die against longitudinal movement toward the work while permitting lateral adjustment of the die sections and of the die as a whole relatively to the frame and power devices connected with the annular fixed frame for reciprocating the tapered arbor.

60 3. In a pipe flanging machine, an expanding annular die

divided into sections and having the outer surfaces of its sections provided with circumferential ribs for acting on the interior surface of the tube to be expanded and their inner surfaces tapered to form a tapered aperture through the die, combined with means for expanding the annular die consisting of a tapering arbor, power devices for reciprocating the arbor, fixed means for holding the annular die in alignment with the arbor and supporting it against movement away from the power devices when the arbor is moved forward in the act of expanding the die.

4. A pipe flanging device consisting of an expanding annular die divided into sections and having the outer surfaces of its sections provided with at least three circumferential ribs for acting on the interior surface of which the outer ribs are of less height than the inner ribs of the tube, to be expanded, combined with means for expanding the annular die and holding it in fixed position, and a circular spring secured to the several sections for normally holding them in collapsed position.

5. A pipe flanging die consisting of an annular structure radially divided into sections and having the outer surface of the sections provided with an outwardly extending annular rib of small cross section for acting upon the interior surface of the pipe within the flange, combined with a fixed support sustained in position independently of the work to hold the die against longitudinal movement, and power devices connected with the fixed support for expanding the die and without putting pressure upon the pipe in the direction of its length.

6. A pipe flanging die consisting of an annular flanged structure radially divided into sections and having the outer surface of the sections provided with an outwardly extending annular rib of small cross section for acting upon the interior surface of the pipe within the flange and radial flanges to prevent longitudinal shifting, combined with an annular permanently fixed abutment ring supported independent of the work having a flat face against which the flanges rest and relatively to which the die may adjust itself in all transverse directions, and a tapering arbor for expanding the die.

7. In a pipe flanging machine, the combination of a fixed abutment ring supported independent of the work, a flanged die removably resting against the abutment ring and divided radially into sections and said sections having their smaller ends extended through the abutment ring and provided with circumferential ribs beyond the ring, means independent of the abutment ring to hold the sections of the die together and an arbor for expanding the die.

8. In a pipe flanging machine, the combination of a hydraulic cylinder and plunger, a housing rigidly connected to the cylinder, an abutment ring removably fitted to the housing, a flanged die resting against the abutment ring and divided radially into sections and said sections having their smaller ends extended through the abutment ring and housing and provided with circumferential ribs beyond the ring, and an arbor for expanding the die carried by the plunger.

9. In a pipe flanging machine, a bed combined with two annular housings bolted to the bed, a hydraulic cylinder secured to one of the housings, bolts connecting the two housings, an abutment ring carried by the other housing, an expanding annular flanging die resting against the abutment ring, a plunger for the cylinder, and a taper arbor carried by the plunger and movable through the flanging die.

In testimony of which invention, we have hereunto set our hands.

JOHN H. ALLEN,
FRANKLIN M. PATTERSON.

Witnesses:

R. M. KELLY,
M. F. DRISCOLL.
